LOCKING AND CLAMPING MEANS FOR
CORE BARRELS

Peter J. Duffy, Houston, Tex.

Application February 15, 1932, Serial No. 592,883

4 Claims. (Cl. 255—72)

The invention relates to an improvement in core barrels of the type which are adapted to be lowered into the drill stem and drill bit during the drilling operation and which may be then removed from the drill bit in order to obtain the core without withdrawing the drill bit from the well bore.

One of the objects of the invention is to provide a core barrel which may be lowered into the drill bit and locked in position to maintain a seal about the core barrel so that the core will not be contaminated by drilling fluid.

Another object of the invention is to provide a core barrel having a plurality of ribs which will center the core barrel with respect to the drill bit to assist in maintaining a seal between the drill bit and the core barrel.

Another object of the invention is to provide a locking or latching mechanism for the core barrel which will engage the drill stem in order to lock the barrel in its lowermost position.

Another object of the invention is to provide a latching mechanism for the core barrel which may readily be released in order to remove the core barrel from its core-catching position.

Still another object of the invention is to provide a tapered portion on the core barrel which will seat upon a similar section of the drill bit.

Another object of the invention is to provide a closed upper end for the core barrel which will prevent the entrance of drilling mud but which will permit the escape of the air entrapped in the core barrel at the time it is positioned in the drill bit.

Another object of the invention is to provide a releasing mechanism for the core barrel latch which may be released by engagement with a suitable hook which can be lowered into the well bore independently of the core barrel.

The invention will be best understood by having reference to the drawing wherein

Fig. 1 is a broken vertical section of a drill stem and drill bit in which the core barrel is positioned.

Fig. 2 is a section looking down on the top of Fig. 1.

Fig. 3 is a section taken on the line 3—3 of Fig. 1 and looking in the direction of the arrows.

Fig. 4 is an elevation, with the ends broken away, of the core barrel illustrating the center ribs and the tapered sealing portion.

It is desirable to obtain a core of the strata which is being drilled and with this in mind various types of core bits and core barrels have been

devised heretofore. The present invention, however, relates to a core barrel which may be releasably positioned within a drill bit which is indicated generally at 2. This bit may be of any desired type but is preferably provided with the water courses 3, which permit the circulation of drilling mud or other fluid. This drilling fluid is used in removing the cuttings from the face of the bit and maintaining the walls of the well bore. The fluid is circulated down through the drill stem 4 and through the drill bit and upwardly in the well bore outside of the drill stem 4. When it is desired to obtain a core of the formation being drilled a core barrel 5 is positioned in the drill bit. The construction of the core barrel is best seen in Fig. 4, which includes the stem 6, the sealing portion 7, and the body 8. The stem 6 is of a diameter to fit smoothly within the opening 9 provided in the drill bit and it is intended that the core barrel will be lowered into the bit so that the stem will pass into the opening 9 in any manner preferred by the operator.

The upper portion of the opening 9 is provided with a plurality of radial slots or grooves 12 which are best seen in section in Fig. 3 and are arranged to receive the ribs 13, which are formed on the stem 6 of the core barrel. These ribs 13 are shown in section in Fig. 1. Directly above the ribs 13 is the tapered section 7, which is adapted to maintain a seal with the tapered seat 15, which is formed in the uppermost part of the opening 9 in the shank 16 of the drill bit. It is intended that when the core barrel is properly seated in the drill bit that the tapered portion 7 will fit tightly in the seat 15 and prevent any of the drilling mud from the drill stem entering the opening 9 around the core barrel. As is well understood, the lower portion of the stem 6 may be provided with suitable cutting edge which usually projects below the cutting face of the drill bit in order to cut the core slightly in advance of the full gauge bore which is being drilled or in some types the core barrel does not extend to the cutting face of the bit. In either event it is intended that the flushing fluid will be excluded from the core and with the aid of the sealing area 7 an uncontaminated core can readily be obtained.

Directly above the tapered portion 7 the body 8 is attached to the lower portion of the core barrel by means of the threads 18. Thus it is possible to make the body 8 of any desired length depending upon the formation being drilled and the length of the core which it is desired to obtain at a single setting of the core barrel.

While the seat 15 is shown as a metal to metal

contact with the core barrel it is intended that the metal may be soft to insure a complete seal or that a special ring or collar of packing material may be provided.

5 The ribs 13 tend to center the core barrel and insure its proper positioning in the drill bit at the same time the seal is being maintained.

In order to latch the core barrel in proper position a latching mechanism has been provided 10 adjacent the top of the body 8 and it is intended that this latching mechanism will be positioned on the uppermost section of pipe which constitutes the body 8. This latching mechanism is mounted upon a cap or plug 20, which serves as 15 a closure for the uppermost section 21 of the core barrel. This plug is provided with a valve 22, which prevents the entrance of fluid into the core barrel from the top but allows the escape of fluids from the inside of the core barrel when sufficient pressure accumulates to overcome the pressure 20 on the top of the core barrel and to raise the valve member.

Mounted on this cap or plug 20 are a plurality 25 of upstanding brackets 23, which are arranged in pairs, as best seen in Fig. 2. These brackets serve as a support for the flexible element 24, which serves to connect the latching arms 25 and 26 so that they may be released.

The brackets 23 serve also to carry the pivot 30 pins 27, upon which the latching arms 25 are mounted. Each of the arms 25 is provided with a shoe 29, which may be of relatively soft material which will engage the drill pipe 4 but which can be deformed by applying a sufficient pull upon 35 the flexible elements 24. It is intended that the arms 25 and 26 will normally assume the position shown in Fig. 1, that is, they will fall by gravity into engagement with the drill stem 4 so that when the core barrel is properly seated they 40 will automatically drop in position and latch the core barrel in the drill pipe. The flexible elements 24 pass through the cross members 30 between the brackets and are suitably supported in this manner. The lower latch arms 26 may be 45 omitted if desired.

It is intended that the elements 24 will be of sufficient length to allow the latching arms 25 and 26 to assume substantially the position shown in Fig. 1 but will not permit them to pass below the center line of the pivot points on which 50 they are mounted.

When it is desired to remove the core barrel it is only necessary to lower a suitable hook or grab tool which will engage the flexible elements 55 at the point 32 intermediate the brackets 23 and a pull may then be exerted upon the chain or element 24. This pull will be transmitted to the arms 25 and 26 and raise them to the dotted line position shown in Fig. 1. This tends to release 60 the core barrel and a continued pull will withdraw it from the drill bit and raise it to the surface. It is intended that suitable core catchers of any well known type can be used in the lower position of the core barrel in order to retain the core 65

within the barrel while it is being removed from the well.

As best seen in Fig. 2, two opposite sets of latching arms have been provided so that the core barrel will be properly centered in the drill stem and the opposite latching arms will create a direct thrust against each other to maintain the core barrel in proper position.

While one specific form of latching mechanism has been shown and described it is contemplated 80 that this may be varied within the scope of the appended claims as desired.

The present application is substantially a duplicate of my prior copending application, Serial 90 #423,164, filed January 24, 1930.

Having described the invention, what I claim as new is:

1. The combination of a core bit and core barrel including a plurality of grooves in said bit, a plurality of ribs on said barrel adapted to interfit with said grooves to center said barrel in said bit, means including friction shoes to hold said barrel in said bit in core-catching position, and additional means including a tapered seat to form a seal between said bit and said barrel. 95

2. A core barrel of the character described including a stem, ribs on said stem adapted to seat in the drill bit to center the core barrel, a sealing portion on said core barrel to engage the drill bit, and means carried by said core barrel to releasably engage the drill stem including a plurality of pivoted friction shoes to hold said core barrel in core-cutting position. 100

3. In combination with a core barrel or pipe a plug removably threaded into one end thereof, 110 a valvular air controlled passage in said plug, a plurality of brackets carried by said plug in axial alignment with the plug, said brackets having holes at their upper ends, a series of radial curved arms having their inner ends pivoted upon the 115 brackets, segmental dogs formed terminally upon the arms, a plurality of chains secured each at one end upon one arm and having its opposite end movably projecting through a hole of the bracket, and a hand hold connected to the free ends of 120 all of the chains by means of which the chains may simultaneously be operated to open or close the arms to place the dogs in and out of gripping position.

4. As a new article of manufacture an anchoring device for a core barrel or pipe consisting of a screw plug having a central through passage arranged axially therein, a check valve controlling the passage, a series of outwardly projecting brackets fixed thereupon, having holes at their 130 upper ends, pivot pins carried by said brackets at their lower ends, a series of arms, each having an inner curved terminal mounted upon one of said pivots, a dog carried by each arm at its outer end, a series of chains or rods projecting through the several holes of the brackets and being secured to one another as well as each to one of the curved arm terminals. 135

PETER J. DUFFY.
